(57) **CLAIM**

The ornamental design for an automotive exterior, as shown and described.

DESCRIPTION

FIG. 1 is a right side/front end perspective view of an automotive exterior in accordance with the present invention, wherein a left side/front end perspective view is a mirror image thereof;

FIG. 2 is a left side perspective view of the automotive exterior of FIG. 1, wherein a right side perspective view is a mirror image thereof; and,

FIG. 3 is a left side/rear end perspective view of the automotive exterior of FIG. 1, wherein the right side/rear end perspective view is a mirror image thereof.

The broken lines are for illustrative purposes only and form no part of the claimed design.

The top plan view is plain and unornamented and is not being claimed as part of the design being claimed.
